UNITED STATES PATENT OFFICE.

GEORGE ALBERT LYON, OF PHILADELPHIA, PENNSYLVANIA, ASSIGNOR TO LYON NON-SKID COMPANY, OF PHILADELPHIA, PENNSYLVANIA, A CORPORATION OF PENNSYLVANIA.

BUFFER FOR MOTOR-VEHICLES.

1,247,300.

Specification of Letters Patent. Patented Nov. 20, 1917.

Original application filed April 21, 1913, Serial No. 762,548. Divided and this application filed November 12, 1915. Serial No. 61,018.

To all whom it may concern:

Be it known that I, GEORGE ALBERT LYON, a citizen of the United States, residing in Philadelphia, Pennsylvania, have invented 5 certain Improvements in Buffers for Motor-Vehicles, (the same being a division of my application Serial No. 762,548, filed April 21, 1913,) of which the following is a specification.

10 The object of my invention is to provide a simple and effective form of buffer for motor vehicles which, while vertically rigid, will oppose a resilient resistance to obstructions in the path of the vehicle, can be 15 readily applied to or removed from the frame of the vehicle, and is equally available for use with frames having their side members of different sizes or shapes and at different distances apart.

20 This object I attain in the manner herein-after set forth, reference being had to the accompanying drawing, in which—

Figure 1 is a perspective view showing in dotted lines the forward end of a motor 25 vehicle and in full lines my improved buffer applied thereto;

Fig. 2 is a top view of the buffer and parts of the side members of the vehicle frame to which it is applied;

30 Fig. 3 is a view, partly in side elevation and partly in section, on the line $a-a$, Fig. 2, and on a larger scale;

Fig. 4 is a perspective view of the buffer detached from the vehicle frame, and

35 Fig. 5 is an enlarged section of certain overlapping members of the buffer and of a clamp whereby they are maintained in rigid vertical relation to one another.

My improved buffer comprises two similar 40 but reversely disposed springs, one carried by one side member of the vehicle frame and the other by the opposite side member thereof, to which they are secured by suitable fastenings. Each of these springs is composed, by preference, of a single rectangular bar of steel or other resilient metal, said bar being of greater width than thickness and the greater dimension of the bar being disposed vertically.

50 Each of the springs comprises a transverse front member 1 and a rearwardly extending member 2, the latter being parallel with the side member of the frame 6 of the

car to which it is secured, and this rearwardly extending or supporting member 2 55 may as indicated in the drawing be connected to the front or impact member of the buffer by a bent and offset intermediate portion so that one part of the buffer may clear the other vertically at crossing points, these 60 intermediate parts of the buffer members being also preferably given an inclined position as indicated. The transversely extending front member 1 is, by preference, of such length as to have its free end extend 65 laterally and also preferably curved rearwardly so as to extend beyond and act as a guard for the front wheel on the opposite side of the car, as shown in Figs. 1 and 2.

The rearwardly extending member 2 of 70 each spring buffer is secured to its corresponding member 6 of the vehicle frame by means of a yoke bolt 7 and a hook bolt 8, the yoke bolt 7 embracing the frame member and having legs passing through openings in the member 2 of the spring, and threaded for the reception of securing nuts 9, as shown in Figs. 2 and 3. The hook bolt 8 overlaps the top of the frame member 6 and passes down through an eye 10 formed 75 at the rear end of the member 2 of the spring, this portion of the bolt being threaded at its lower end for the reception of a securing nut 11, as likewise shown in Figs. 2 and 3.

85 The transversely extending front members 1 of the springs overlap and reinforce one another and lie side by side so as to increase the yielding resistance of this central or impact portion of the buffer, and in order to 90 rigidly retain them in proper vertical relation to one another and yet permit transverse adjustment of one in respect to the other in adapting the buffer to cars having side members at different distances apart, 95 said overlapping front members of the springs are engaged by clamping yokes or clips 5 each having parallel jaws through which passes a bolt 5^a, this bolt having a head bearing upon one of said jaws and being threaded for the reception of a nut bearing upon the other jaw, whereby the clamp can be loosened when transverse adjustment of the springs is desired, and then again tightened to rigidly confine the 100 springs.

The springs constituting the buffer are practically rigid in a vertical direction, have a vertically rigid support upon the vehicle frame, and are rigidly held in vertical relation to one another by means of the clamping yokes 5, hence the buffer will always preserve its proper vertical relation to the side members of the machine frame and to the wheels and will be free from any tendency to sag, but will, at the same time, oppose a resilient resistance to fore and aft strains or to blows upon it applied in the direction of the arrow Fig. 2.

I claim:

- 15 1. The automobile buffer consisting of two similar integral spring steel strips having many times greater vertical width than thickness to render them relatively rigid vertically while resiliently yielding in horizontal directions, each of said strips having a rearwardly extending attaching member to be attached to the side member of the frame of the automobile and having a transversely extending impact receiving member and a free end extending laterally into protective position in front of the automobile wheel and rearwardly curved, the impact receiving members of said strips overlapping substantially throughout the distance between the side frames of the automobile to stiffen and strengthen this part of the buffer and frictionally gripping connecting clips adjustably connecting said impact receiving members and holding them against relative vertical movement, said attaching members being connected to said impact receiving members by bent offset portions of said strips so that one part of the buffer clears the other vertically at the crossing point.

40 2. The automobile buffer consisting of two similar integral spring steel strips having many times greater vertical width than thickness to render them relatively rigid vertically while resiliently yielding in horizontal directions, each of said strips having a rearwardly extending attaching member to be attached to the side member of the frame of the automobile and having a transversely extending impact receiving member and a free end extending laterally into protective position in front of the automobile, the impact receiving members of said strips overlapping substantially throughout the distance between the side frames of the automobile to stiffen and strengthen this part of the buffer and frictionally gripping connecting clips adjustably connecting said impact receiving members and holding them against relative vertical movement.

55 3. The automobile buffer consisting of two similar integral spring steel strips having many times greater vertical width than thickness to render them relatively rigid vertically while resiliently yielding in horizontal directions, each of said strips having

a rearwardly extending attaching member to be attached to the side member of the frame of the automobile and having a transversely extending impact receiving member and a free end extending laterally into protective position in front of the automobile wheel, the impact receiving members of said strips overlapping to stiffen and strengthen this part of the buffer and connecting clips adjustably connecting said impact receiving members and holding them against relative vertical movement.

4. The automobile buffer consisting of two similar integral springs relatively rigid vertically while resiliently yielding in horizontal directions, each of said springs having a rearwardly extending attaching member to be attached to the automobile and having a transversely extending impact receiving member and a free end extending laterally into protective position in front of the automobile wheel and rearwardly curved, the impact receiving members of said springs overlapping substantially throughout the distance between the side frames of the automobile to stiffen and strengthen this part of the buffer and connecting means connecting said impact receiving members and holding them against relative vertical movement. 80 85 90

5. The automobile buffer consisting of 95
two similar integral springs relatively rigid vertically while resiliently yielding in horizontal directions, each of said springs having a rearwardly extending attaching member to be attached to the automobile and 100 having a transversely extending impact receiving member and a free end extending laterally into protective position in front of the automobile wheel, the impact receiving members of said springs overlapping to 105 stiffen and strengthen this part of the buffer and connecting means adjustably connecting said impact receiving members and holding them against relative vertical movement.

6. The automobile buffer consisting of two similar integral springs, each of said springs having a rearwardly extending attaching member to be attached to the automobile and having a transversely extending impact receiving member and a free end extending laterally into protective position in front of the automobile wheel, the impact receiving members of said springs overlapping to stiffen and strengthen this part of the buffer and connecting means connecting said impact receiving members and holding them against relative vertical movement.

7. The automobile buffer consisting of two similar integral springs, each of said springs having a rearwardly extending attaching member to be attached to the automobile and having a transversely extending impact receiving member and a free end extending laterally into protective position in 130

front of the automobile wheel, the impact receiving members of said springs overlapping to stiffen and strengthen this part of the buffer and connecting means adjustably connecting said impact receiving members and holding them against relative vertical movement, said attaching members being connected to said impact receiving members by bent offset portions of said springs so that one part of the buffer clears the other vertically at the crossing point.

8. The automobile buffer consisting of two oppositely disposed vertically rigid flat spring strips, each adapted to be secured to the vehicle and having a transverse member, said transverse members overlapping and reinforcing each other and having free ends extending to and ending in a protective position in front of the wheels of the vehicle.

9. The automobile buffer comprising vertically rigid springs having transverse members and rearwardly extending attaching members, said transverse members being adjustably connected to reinforce each other and having free ends extending to and ending in a protective position in front of the wheels of the automobile and means for securing the rearwardly extending attaching members to the frame of the automobile.

10. The automobile buffer comprising vertically rigid springs having transverse members and rearwardly extending attaching members, said transverse members overlapping and reinforcing each other and connected together in vertically rigid alinement and having free ends extending to and ending in a protective position in front of the wheels of the automobile.

11. The automobile buffer comprising two oppositely disposed vertically rigid flat spring strips each adapted to be attached to the vehicle and having free ends extending to and ending in a protective position in front of the wheels of the automobile and adjustably connected to another part of the buffer to form a front impact member extending in front of the vehicle.

12. The automobile buffer comprising oppositely disposed vertically rigid spring strips each adapted to be secured to the vehicle and having an outwardly extending free end and adjustably connected in vertically rigid alinement to a transversely extending portion of the buffer to enable the buffer to be attached to vehicles having attaching portions at different distances apart.

13. The automobile buffer comprising two oppositely disposed vertically rigid spring strips adapted to be attached to the vehicle and having free ends extending to and ending in a protective position in front of the wheels of the automobile and adjustably connected to another part of the buffer

to form a front member of the buffer and held in vertically rigid alinement therewith.

14. The automobile buffer having a central reinforced impact portion comprising a plurality of overlapping vertically rigid flat spring strips adjustably connected together in a vertically rigid manner, two of said strips having free ends extending to and ending in a protective position in front of the wheels of the vehicle and means by which said buffer is adapted to be secured to the supporting member of vehicles, said buffer being adapted to be connected to vehicle supporting members located at different distances apart.

15. The automobile buffer having a central reinforced impact portion comprising a plurality of overlapping spring strips adjustably connected together, two of said strips having free ends extending to and ending in a protective position in front of the wheels of the vehicle and means by which said buffer is adapted to be secured to the supporting members of vehicles, said buffer being adapted to be connected to vehicle supporting members located at different distances apart.

16. The automobile buffer having a central reinforced impact portion comprising a plurality of overlapping spring strips adjustably connected together, two of said strips having free ends extending to and ending in a protective position in front of the wheels of the vehicle and means by which said buffer is adapted to be secured to the supporting members of vehicles.

17. The automobile buffer consisting of two oppositely disposed vertically rigid flat spring strips each having a transverse member extending to and ending in a protective position in front of the wheels of the vehicle, means adjustably connecting said transverse members so that they overlap and reinforce each other in the central impact portion of the buffer, and means to secure said spring strips to the vehicle.

18. The automobile buffer consisting of two oppositely disposed vertically rigid spring strips each having a transverse member extending to and ending in a protective position in front of the wheels of the vehicle, said transverse members overlapping and reinforcing each other throughout the central impact portion of the buffer extending substantially between the side frames of the vehicle, and means to secure said spring strips to the vehicle.

19. The automobile buffer having a central reinforced impact member comprising a plurality of overlapping vertically rigid spring strips adjustably connected together to be substantially vertically rigid throughout said reinforced portion and to have their free ends located at varying distances

apart, two of said strips having free ends extending to and ending at the sides of the buffer and means by which said buffer member is adapted to be secured to the supporting members of vehicles located at different distances apart.

20. The automobile buffer having a central reinforced impact member comprising a plurality of overlapping vertically rigid 20
19 spring strips adjustably connected together to be substantially vertically rigid throughout said reinforced portion and to have their free ends located at varying distances apart, two of said strips having free ends extending to and ending at the sides of the buffer and means by which said buffer member is 25
18 adapted to be secured to the vehicle.

21. The automobile buffer having a central reinforced impact member comprising a plurality of overlapping vertically rigid 20
19 spring strips connected together, in vertically rigid alinement, two of said strips having free ends extending to and ending at the sides of the buffer and means by which said buffer member is adapted to be 25 secured to the vehicle.

In testimony whereof, I have signed my name to this specification, in the presence of two subscribing witnesses.

GEORGE ALBERT LYON.
